UNITED STATES PATENT OFFICE.

CHARLES E. BATHRICK, OF CHICAGO, ILLINOIS, ASSIGNOR TO FREDERICK C. AUSTIN,
OF CHICAGO, ILLINOIS.

POWER TAMPING-MACHINE.

1,174,803.

Specification of Letters Patent. Patented Mar. 7, 1916.

Application filed June 30, 1909. Serial No. 505,206.

To all whom it may concern:

Be it known that I, CHARLES E. BATHRICK, a citizen of the United States, residing at Chicago, in the county of Cook and State of Illinois, have invented certain new and useful Improvements in Power Tamping-Machines, of which the following is a specification.

Objects of my invention are to provide a compact and generally efficient power tamping machine particularly adapted for tamping down material used in street paving and other kindred work; to insure a quick and efficient tamping action; to provide a power tamping machine which can be easily controlled and moved from place to place by an attendant, and to provide certain improved details serving to increase the efficiency of the machine, and to render it extremely useful for the purposes for which it is intended.

In the accompanying drawings: Figure 1 is a side elevation of a power tamping machine embodying my invention. Fig. 2 is a top plan of Fig. 1. Fig. 3 is a longitudinal 25 sectional elevation, the section being on line 3, 3, in Fig. 2. Fig. 4 is an enlarged detail view partly in elevation and partly in section on line 4, 4, in Fig. 3.

A indicates a truck or carriage provided with a set of vibratory tampers B, B', B² and B³, and an engine C for operating the tampers and also for propelling the truck. The tampers are respectively secured to the outer ends of vibratory spring arms D, D', D² and D³, which extend longitudinally under the body frame 1 of the truck and project beyond one end thereof. These spring tamper arms have their inner end portions hinge-connected with the truck so as to permit them to have a suitable extent of up and down vibratory swing, the action of such arms with the tampers thereon being what may be termed a whipping action whereby the arms, which overhang the street surface or road bed, when the machine is in use, will when actuated cause the tampers to slap down upon and effectively tamp the material that is to be packed or tamped. With further reference to the spring action, each tamper arm is a flexible elastic metal bar or arm, whereby its individual spring action renders the tamping action of the tamper thereon exceedingly effective. Referring in detail to means for supporting and operating the tamper arms, E indicates

a transversely arranged shaft forming a pivot or pintle for a series of vibratory rigid or substantially rigid arms or members F to which the inner end portions of the spring tamper arms are secured. These 60 vibratory members F are connected with the crank portions of a rotary transverse shaft G by means of pitman H, whereby the rotation of the shaft will vibrate the spring tamper arm. As shown in Fig. 2, the shaft 65 G is provided with a middle crank bend 2 with which a pair of these pitmen H are connected, and between said middle bend and each of its ends it is provided with a crank bend 3 to which a single pitman H is 70 attached, the end bends 3 being the reverse of the middle bend 2. By this arrangement the middle crank portion 2 operates a pair of tampers which with relation to the set or series are between the two tampers respectively at opposite ends of the set or series, the crank portion 3 for actuating one pair being timed the reverse of the crank portion 2 for actuating the remaining pair of tamping devices. In this way suitable balance and steady operation are insured. The 75 rotary cranked shaft G is mounted upon the body frame of the truck and driven from the transversely arranged rotary engine shaft 4 by means of a driving belt 5 connecting a 80 pulley 6 fixed on the engine shaft with a pulley 7 fixed on the cranked shaft G.

The truck body is wheel supported at a point between its ends and suitably balanced so that an attendant standing at one 90 end of the truck can readily tilt the truck body about the axis of such middle supporting wheel for the purpose of depressing or elevating the range of vibratory action on the part of the tampers. While either end 95 of the truck might be consistently termed its forward or rear end, the end of the truck from which the tamper arms project is hereinafter termed the rear end of the truck, its opposite end being therefore referred to 100 as its forward end. The spring tamper arms which extend beyond the rear end of the truck body, incline upwardly and rearwardly or outwardly when the truck is in normal position, that is to say—when the 105 truck is not abnormally tilted from its normal position of rest in which it is supported upon the middle supporting wheel or roll, and a caster wheel I at the lower end of a leg 8 on the forward end of the truck 110

body. The extent of vibratory play of the tamper arms is also such that when the truck is not tilted in direction to depress its rear end, the extent of down swing on the 5 part of the tamper arms will not be sufficient to bring the tamper down upon the material that is on the road bed ready to be tamped. In order however to permit the 10 desired tamping, the truck can be tilted in direction to depress its rear end, thereby lowering the tamping devices sufficiently to permit the tampers to impact upon the material laid under them. To facilitate manipulation of the truck it is provided at its 15 forward end portion with a suitable handle K which is available to an attendant. The middle supporting wheel or roll is shown divided into two wheel-portions or roll sections 9 and 10. These roll or roller sections 20 are arranged on a transverse axle L which is supported at its end portions in bracket bearings 11 depending from opposite sides of the body frame of the truck, one of these bearings being shown in Figs. 25 1 and 3, and the other being understood to be present in Figs. 1 and 2.

As a means for propelling the truck in either direction at will, the axle L, to which the roll sections 9 and 10 are secured, is 30 provided with a sprocket 12 fixed thereon and arranged between the opposing ends of the roll sections 9 and 10. The driven sprocket 12 thus arranged on the middle 35 supporting axle L is connected by an endless driving chain 13 with a driving sprocket 14 secured on a transverse rotary shaft 15 which is in turn mounted upon the truck body. The rotary shaft 15 carries a friction wheel M which is secured thereon and operated 40 in either direction at the will of an attendant. The device for thus actuating the friction wheel M comprises a pair of friction rolls N and N' which can be caused to engage the friction wheel M in alternation. 45 These friction rolls N and N' are mounted upon a vibratory support P which is hinged by pivot 16 to a bracket on the truck body, the arrangement being such that the support P can be turned so as to place the face 50 of roll N or the face of roll N' in frictional engagement with the face of wheel M, as may be desired. The hub portion of roll N' is formed or provided with a gear 17, (see particularly Fig. 4), and the hub portion of 55 roll N is provided with a like gear 18 which meshes with the gear 17. The roll N' is fixed upon an axle 19 which is mounted upon the vibratory support or bearing member P and provided at one end with a chain 60 or link belt sprocket 20 fixed thereon. This sprocket 20 is connected by a drive chain or belt 21 with a driving sprocket 22 secured on the rotary engine shaft 4 (Fig. 2). The vibratory member P which may also be termed 65 a bell-crank, can be adjusted in position by

an attendant standing at the forward end of the truck, and to such end the bell-crank is secured to pivot 16 which is supported for reversely rotative or oscillatory action and in turn provided with a crank arm 23. The 70 lower end of a bar 24 is fastened to the end of crank arm 23, the upper end of bar 24 being hinged to the rear end of a vibratory push and pull bar or rod 25 arranged to slide in a guide eye 26 on the truck handle K. The forward end of rod 25 has a handle portion 27 which can be readily taken hold of by an attendant having hold of the hand portion 28 of the truck handle K. With the arrangement of members thus described, the bell-crank P can be turned in a direction dependent on the direction in which rod 25 is longitudinally moved and as the intermeshing gears 17 and 18 relatively turn in opposite directions, the direction in which axle L is turned will depend on which one of the friction rolls N and N' is in frictional engagement with the wheel M.

As shown in Figs. 1 and 3, the visible 90 bracket 11 is provided with a rearwardly extending arm portion 29, in which one end of the shaft or pivot E is mounted, it being understood that the opposite end of the shaft or pivot E is mounted in a like arm 95 portion of a like bracket at the opposite side of the truck. When therefore the truck is tilted so as to depress its rear end portion, the brackets 11 will tilt about the axis of axle L and their arm portions 29 will be lowered proportional to the extent to 100 which the truck frame is tilted.

What I claim as my invention is:

1. In a power tamping machine, a rotary shaft provided with relatively reverse crank bends, a plurality of pitmen connected with said crank bends, a rigid arm connected with each pitman and mounted to swing on a pivotal axis, a flexible tamper arm mounted to swing about said pivotal axis and connected with said rigid arm adjacent to said axis, tamping members rigidly mounted on said flexible arms, and means for rotating said crank shaft to whip the flexible arms up and down. 105

2. In a power tamping machine, a wheel supported tilting truck, brackets depending therefrom, vibratory tamper arms provided with tampers, a hinged connection between the tamper arms and brackets, the tampers 110 being sufficiently elevated to clear the ground or bed surface when the truck is in normal position, but to act upon the bed surface when the truck is tilted in direction to lower the tampers and means for driving the tamper arms upward and downward. 115

3. In a power tamping machine, a wheeled truck, a rotary power driven shaft provided with reverse crank bends and supported upon the rear end portion of the truck, a 120

set of vibratory spring tamper arms extending under and beyond the rear end portion of the truck body and having their rear outer ends provided with tampers, a shaft 5 supported beneath the truck, the front ends of the tamper arms being pivotally mounted thereon and power transmitting connections between the spring tamper arms and the rotary crank shaft and operative to whip said 10 tamping arms up and down.

4. In a power tamping machine, a truck provided with tamping devices, a power supplying member on said truck, operative connections between said power supplying 15 member and said tamping devices, and means for moving the truck, said means comprising a friction wheel mounted upon the truck, a vibratory member also supported upon the truck and provided with 20 friction wheels having intermeshing gears, whereby said friction wheels can engage the friction wheel in alternation, means for driving the friction wheels on the vibratory member, a supporting wheel for the truck, 25 a suitable power transmitting device for driving the supporting wheel from the friction wheel, and an adjusting device for moving the vibratory member upon which the pair of friction wheels is mounted.

5. In a tamping machine, the truck body provided with bracket bearings, an axle journaled in said bearings and provided with a supporting wheel, said bracket bearing having rearwardly extending arm portions, vibratory tamper arms provided with 35 tampers and hinge-connected with the rearwardly extending arm portions of said brackets, and mechanism supported upon the truck body for whipping said tamper 40 arms up and down.

6. In a tamping machine, the combination with a truck, brackets depending therefrom, wheels journaled within said brackets on which the truck may be tilted, to bring the 45 machine into action, a shaft journaled within said brackets, flexible arms pivotally mounted upon said shaft and extending below the truck, each arm carrying at its outer end a rigidly mounted tamper and 50 means for whipping the tampers up and then down.

7. In a tamping machine, the combination

of a truck, an engine mounted on said truck, wheels carrying the major portion of the weight of said truck and its supported mechanism, a pivot near said wheels, flexible arms mounted on said pivot and each carrying at its outer end a rigidly mounted tamper, rigid arms also mounted on said pivot, said arms being connected with said spring arms 60 adjacent to said pivot, and connecting means for utilizing the power of said engine in moving said rigid arms about said axis, thereby positively whipping said flexible arms downward against the surface to be 65 tamped.

8. In a tamping machine, the combination of a truck body, an engine mounted on said body, power transmitting mechanism carried by said body and connected to transmit 70 power from said engine, a plurality of wheels mounted near the center of gravity of said truck body, a plurality of spring arms pivoted at one end to said truck near said wheels, each of said spring arms carrying a tamper rigidly mounted thereon, connections between said power transmitting mechanism to whip said spring arms upward and downward, and a handle whereby the operator may tilt said truck body on its 80 supporting wheels to bring said tampers into and out of operative contact with the surface to be tamped.

9. In a power tamping machine, a truck provided with tamping devices, wheels for 85 supporting the truck, means for rotating the wheels comprising a friction wheel mounted upon the truck, a bracket mounted upon the truck, friction wheels carried by said bracket, means for operatively connecting 90 the friction wheels of the bracket together, means for rotating one of the friction wheels carried by the bracket, means for throwing the friction wheels carried by the bracket into and out of engagement with the friction 95 wheel carried by the truck whereby the truck may be moved in opposite directions and means for operating the tamping devices, substantially as described.
